Attorney # UNITED STATES PATENT OFFICE.

LOUIS H. KIRK, OF NEW YORK, N. Y., ASSIGNOR TO PEG LOCK BLOCK COMPANY INC.,
OF NEW YORK, N. Y., A CORPORATION OF NEW YORK.

TOY.

1,192,530.

Specification of Letters Patent. Patented July 25, 1916.

Application filed April 1, 1916. Serial No. 88,198.

To all whom it may concern:

Be it known that I, LOUIS H. KIRK, a citizen of the United States, and resident of New York, in the county of New York and 5 State of New York, have invented certain new and useful Improvements in Toys, of which the following is a specification.

My invention relates generally to toys, and has special reference to that class of toys 10 comprising sets of building elements of various shapes and sizes adapted for employment in building toy structures of various kinds, and which sets of building elements are put up in suitable boxes or containers. 15 The sets of building elements to which my present invention has particular reference include both rods and disks, the latter having central perforations to receive the ends of the rods, whereby, upon placing a pair of 20 disks on the opposite ends of one of the rods, a wagon axle and supporting wheels may be provided. To utilize such an axle and supporting wheels in making a toy wagon, a wagon body of course is necessary. Such a 25 body, however, obviously would materially add to the bulk and expense of the toy. Therefore, it has been the object of my present invention to provide a wagon body for use in connection with the axle and wheels 30 referred to, that will not add to the bulk or expense of the toy. This object I accomplish by adapting the regular box or container in which the toy is contained for use as a wagon body, in the manner hereinafter 35 disclosed.

Referring now to the accompanying drawings forming part of this specification, Figure 1 is a perspective view of a container embodying my invention, the same being 40 shown as it appears when used as a container for the toy, and Fig. 2 is a similar view of the container, the same in this instance being shown as a wagon body mounted on axles and wheels provided by the toy 45 elements.

Similar reference characters indicate like parts on the several figures of the drawings.

The container for the toy may be of any desired form, size or material. In the present case it is a rectangular wooden box *b*, provided at its top with a removable cover *c* having the usual tongue-and-groove sliding connection therewith. The toy contained in this box will ordinarily comprise a number 55 of cubes, disks and rods, as indicated at 2, 3

and 4, respectively, the cubes and disks being provided with holes or perforations to receive the rods in making connection between the parts in the building of the desired toy structures. Certain of these toy parts, as 60 hereinbefore referred to, may be utilized as wagon supporting axles and wheels by entering the opposite ends of the rods into or through central perforations in the disks as shown. In order to utilize the container *b* 65 as a wagon body to be mounted on these axles and wheels, the same is provided with openings 5 in its opposite side walls to receive the rods 4, as shown in Fig. 2, the said rods being of sufficient length to extend beyond the opposite sides of the container for connection with the disks, and the openings 5 being so spaced from the bottom of the container as to insure the latter being supported by the disks a desired height from the 70 surface on which the disks rest.

If it is desired to make a two-wheeled vehicle or cart, one pair of wheels or disks may be employed and one pair of openings 5 in the box or container may be centrally 80 or otherwise located, but if it is desired to make a four-wheeled vehicle, two pairs of openings 5 will be provided in the container, one pair near each end thereof, as shown. 85

As a means to conveniently draw or otherwise manipulate the wagon, it is desirable that the same should be provided with a wagon tongue, and as a means to provide this the container is provided with an opening 6 in its front end wall to receive one of the rods 4, as shown in Fig. 2, which rod will be tightly fitted in said opening 6. 90

As a means to provide for holding the cover *c* in closed position and also provide 95 for the support of a seat or other superstructure on the wagon body *b*, openings or perforations 7 and 8 are also formed in the cover and bottom respectively, in positions registering with each other, through which may be passed one of the rods 4 with its upper end projecting above the cover for connection with other of the building elements, such for instance the cube shown, to which may be connected any desired form 100 of toy structure.

What I claim is:

1. A toy comprising building elements and a container therefor, the building elements including rods and perforated disks 110

adapted to be fitted on said rods, and the container being provided with openings in its opposite sides to removably receive one of the rods with disks located on its opposite ends exterior of the container, for the purpose described.

2. A toy comprising building elements and a container therefor, the building elements including rods and perforated disks 10 adapted to be fitted on said rods, and the container being provided with two pairs of openings in its opposite sides and adjacent the opposite ends of the container to removably receive two rods with disks on their 15 opposite ends exterior of the container, for the purpose described.

3. A toy comprising building elements and a container therefor, the building elements including rods and perforated disks 20 adapted to be fitted on certain of said rods, and the container being provided with openings in its opposite sides and also with an opening in one end thereof, the openings in the sides of the container being adapted to 25 removably receive one of the rods with disks on its opposite ends exterior of the container serving as wheels, and the opening

in the end of the container adapted to removably receive one of the rods to serve as a wagon tongue.

4. A toy comprising building elements and a container therefor, the building elements including rods and perforated disks 30 adapted to be fitted on certain of said rods, and the container having a removable cover and being provided with openings in its opposite sides and also in the cover and bottom thereof, the openings in the sides of the container being adapted to removably receive one of the rods with disks on its 35 opposite ends exterior of the container serving as wheels, and the openings in the cover and bottom being oppositely located and adapted to removably receive one of said rods and support the same with one end projecting 40 above the cover, for the purpose described.

Signed at New York, in the county of New York, and State of New York, this 20th day of March A. D. 1916.

LOUIS H. KIRK.
